UNITED STATES PATENT OFFICE

EMIL CRISAND, OF NEW HAVEN, CONNECTICUT, ASSIGNOR TO HENRY ST. JOHN, OF SAME PLACE.

DESIGN FOR EMBROIDERY-PATTERNS.

Specification forming part of Design No. 7,893, dated November 24, 1874; application filed November 7, 1874.
[Term of Patent $\frac{3}{4}$ years.]

CASE E.

To all whom it may concern:

Be it known that I, EMIL CRISAND, of New Haven, in the county of New Haven and State of Connecticut, have invented a new Design for Embroidery - Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern, intended especially for perforated board; and it consists in the peculiar configuration and ornamentation of the motto, as shown in the accompanying illustration.

The motto forming the base of this design is "No Cross No Crown," which is represented by the word "No," the figure of a cross, another word "No," and the figure of a crown. The form of the letters and the cross and crown, as clearly shown in the accompanying illustration, constitute the principal features of this design.

The ornamentation and filling of the pattern is of a scroll-work character, interwoven with the words and figures, as shown in the accompanying illustration.

I claim—

The design for embroidery-patterns herein described, consisting of the motto "No Cross No Crown," in form and ornamentation as shown in the accompanying illustration.

EMIL CRISAND.
